COMBINATION STORM SASH OPERATOR
AND FASTENER

Chester O. Goserud, St. Paul, Minn.

Application December 12, 1930, Serial No. 501,764

Renewed November 30, 1932

23 Claims. (Cl. 20—55)

My invention relates to storm sash operators and fasteners and particularly to a device adapted to be used in conjunction with a double hung window having a frame, an upper sash and a lower sash slideable relative thereto and formed with meeting rails, and a storm sash pivoted to said frame.

An object of the invention resides in providing a device whereby the storm sash may be opened 10 and closed through movement of one of the sliding sash of the window.

Another object of the invention resides in providing a sash operator and fastener adapted to hold the storm sash in any adjusted position.

15 A still further object of the invention resides in providing a sash operator and fastener in which the storm sash is locked from opening when the sliding sash by means of which it is operated is closed.

20 In carrying out the invention, I employ a pair of jointed arms, one of the arms being pivoted to the window frame and the other to the storm sash.

Another object of the invention resides in 25 constructing said arms of substantially the same length and in disposing the pivots therefor so that said pivots substantially coincide when the storm sash is closed, permitting the arms to be swung outwardly to open the storm sash and to be swung into overlying position to close the storm sash and to be further swung jointly to lock the storm sash in closed position.

An object of the invention resides in providing 30 a lever for swinging one of said arms to operate the device.

A feature of the invention resides in attaching 35 said lever to the arm pivoted to the window frame.

An object of the invention resides in providing 40 a link connecting one of the sliding sash with said lever.

A feature of the invention resides in attaching 45 said link to the upper sliding sash.

A still further object of the invention resides in connecting said link to the underside of the 50 meeting rail of the upper sash and in forming said link offset to permit said link to be moved substantially through an angle of 180 degrees.

Another object of the invention resides in providing 55 a stop acting between the arm pivoted to the storm sash and the storm sash for preventing said arm from moving toward said sash during the opening thereof so as to cause the storm sash to readily open upon movement of said lever.

A feature of the invention resides in construct-

ing the parts detachable so that the storm sash and operator may be readily removed from the window frame whenever desired.

Other objects of the invention reside in the details of construction thereof and in the combination of elements hereinafter illustrated and/or described.

In the drawings:

Fig. 1 is a perspective view of a window illustrating an embodiment of my invention applied thereto.

10 Fig. 2 is a fragmentary longitudinal sectional view of the window shown in Fig. 1, illustrating both the storm sash and the sliding sash in open position.

15 Fig. 3 is a view similar to Fig. 1 showing the storm sash in substantially closed position and the sliding sash in partially closed position.

Fig. 4 is a view similar to Fig. 3 showing the storm sash in closed position and the operator 20 locked.

Fig. 5 is a elevational sectional view taken on line 55 of Fig. 4.

Fig. 6 is an elevational sectional view taken on line 6—6 of Fig. 4 and drawn to a larger scale.

Fig. 7 is an elevational sectional view taken on line 7—7 of Fig. 4 and drawn to a larger scale.

For the purposes of illustrating the application 30 of my invention, I have shown in Fig. 1 a window indicated in its entirety at 10 which comprises a window frame 11 arranged with stops 12 and 13 to slidably support the usual upper and lower window sash 14 and 15. The sash 14 is formed with stiles 26, an upper rail 27 and a meeting rail 28 while the lower sash 15 is similarly constructed with stiles 29, a lower rail 30 and an upper rail 31, both of which support window panes in the usual manner.

In conjunction with the frame 11, a storm window 16 is illustrated which is constructed with stiles 17 and 18 connected together through rails 19, 20 and 21 and supporting window panes in the usual manner. The storm sash 16 is hingedly connected to the header 22 of the frame 11 through sash hangers 23 and 24 in the usual manner so as to permit of the swinging of the sash outwardly as shown in Fig. 1 or to permit the same to be swung into the rabbett adjacent the stop 13 formed in frame 11 and indicated at 25.

For the purpose of readily manipulating the storm sash the lower rail 21 thereof may be provided with a pull or knob whereby the sash may be opened or closed as customary.

My invention preferably employs two sash operators and fasteners, one attached to the stile 17 and the other attached to the stile 18 of the storm

sash 16 and to the stops 13 of the frame 11. Both of these devices are identical in construction, except that the one is left handed and the other right handed and for this reason, only the sash 5 operator and fastener attached to stile 18 of the storm sash has been illustrated and described in the specification. This sash operator is indicated in its entirety at 32.

The sash operator and fastener 32 consists of 10 two arms 33 and 34 substantially equal in length which are provided with heads 36 and 37 pivotally connected together through a rivet 35. These arms are pivoted at their opposite ends to the stop 13 of frame 11 and to the stile 18 of storm sash 16. 15 The pivots for these two arms are located substantially equal distances from the hangers 23 and 24 so as to permit of the closing of the sash, as will be presently described in detail. When the sash is open, the arms are extended, as shown in Fig. 20 2, and when the sash is closed, these arms come together as shown in Fig. 4, so that the arms overlie one another. After the arms have become so positioned the said arms may be swung jointly from the position shown in Fig. 3 to that shown 25 in Fig. 4. When disposed as shown in Fig. 4 the sash is held in place and locked to prevent opening of the sash without the swinging of said arms.

For the purpose of attaching the arm 34 to the 30 stile 18 of the storm window 16, I employ a bracket which is indicated in its entirety at 40. This bracket is preferably bent from a piece of sheet metal and is formed with a base 41 and with a flange 42 extending outwardly therefrom. The 35 base 41 may be secured to the stile 18 of the storm sash by means of wood screws 43 so that the flange 42 extends inwardly toward the sash 14 and 15. The extreme end of the arm 34 is formed with a head 39, Figs. 5 and 6, which is 40 pivotally connected to the flange 42 of bracket 40 through a rivet 44. By means of this construction the arm 34 is pivotally mounted upon the bracket 40 so that the same may be swung through the various positions shown in Figs. 2, 3 and 4.

45 The arm 33 is pivotally connected to the stop 13 of frame 11 of the window through a mounting plate 45. This mounting plate is preferably constructed of sheet metal, the same as the bracket 40 and is formed with foot portions 46 at the ends 50 thereof and with a body portion 47 offset from the foot portions. This mounting plate is preferably of a width not to exceed the width of the stop 13 and is secured thereto through screws 48 which extend through the foot portion 46. At the center of the body portion 47 is formed a circular opening 49, Fig. 6, which provides a bearing for the arm 33. The arm 33 is provided at the end 55 thereof opposite the rivet 35 with a circular head 50 which has riveted to it a short stud 51 forming a trunnion 52 issuing outwardly therefrom and adapted to be inserted within the opening 49. By means of this construction, the arm 33 may be detachably connected to the mounting plate 45 and when attached is journaled for rotation 60 65 therein.

For the purpose of swinging the arm 33 to open and close the storm sash 16, a lever 53 is employed 70 which issues outwardly from the head 50 of said arm and which may, if desired, be integrally constructed with reference thereto. The lever 53 makes an acute angle with the arm 33 and is adapted to swing from the position shown in Fig. 2 to that shown in Fig. 4. During the movement of said lever the storm sash 16 is caused 75 to move from its open position as shown in Fig. 2

to its closed position as shown in Fig. 4. The lever 53 has pivotally attached to it an operating link 54 which is provided at one end thereof with a head 55 adapted to be pivotally connected to said lever through a rivet 56 best shown in Fig. 5. The link 54 is formed at its other end with a head 62 and is constructed adjacent said head with an offset portion 61, the function of which will be subsequently more fully described.

The link 54 is pivotally connected to a bracket 10 57 attached to the underside of the rail 28 of sash 14. This bracket is preferably bent from a piece 15 of sheet material and is formed with a base 58 and with a flange 59 extending outwardly therefrom. The base 58 may be secured to the underside of the rail 28 through screws 60 so that the flange 59 extends downwardly from the lower portion of the sash 14. The flange 59 of bracket 57 is provided with a short stud 63 which is securely riveted to said flange and which is provided with 20 a portion 64 serving as a trunnion. This trunnion is received within an opening 65 in the head 62 which serves to rotatably support the link 54 with respect to the bracket 57.

The various arms 34, 33, lever 53 and link 54 25 are all permanently pivoted to one another and to the bracket 40 previously referred to. These parts may hence be removed with the storm sash when the storm sash is disconnected from the window. In applying the sash to the window the 30 sash is first hung in the sash hangers 23 and 24 in the usual manner. Stud 52 is next applied to the opening 49 in the mounting plate 45. The sash 14 is thereafter lowered and the link 54 moved until the stud 54 on bracket 57 is engaged 35 with the opening 65 in said link. Such engagement is procured by springing the entire linkage sufficiently to cause the head 62 to clear the stud 64. Due to the fact that the two studs 64 and 52 can be disengaged from the respective sockets in 40 which they are disposed only on movement of the linkage in opposite directions, said studs are retained through the resiliency of the linkage in 45 proper operating relation to the associate structure.

As a result of the particular proportioning and 50 design of the lever 53 and link 54, said lever occupies the position shown in Fig. 2, when the upper sash 14 is lowered. The lever 53 may be 55 swung into the position shown in Fig. 3 when the upper sash is partially raised, in which position the storm sash is almost closed and the two arms 33 and 34 are in substantial alignment. As the sash 14 is further raised the storm sash is completely closed and both arms 33 and 34 thereafter move in unison. When the upper sash is completely closed as 60 shown in Fig. 4 the two arms 33 and 34 are disposed in overlying relation and occupy a substantially horizontal position. When the parts are so arranged the linkage serves to lock the storm window closed to prevent opening thereof through the pull attached to the same or by applying pressure directly to the storm sash. The offset 61 in the link 54 serves to permit said link 65 to swing substantially through an angle of one hundred and eighty degrees giving a maximum of movement of the various parts. This offset 61 causes said link to clear the rail 28 when the upper sash is in its lowermost position and the 70 said link is raised.

To cause the linkage to break when the upper sash is in its two extreme positions so that the lever 53 may be swung to open and close the storm sash, a finger 66 is employed which is struck out 75

of the material of the head 55 of link 54 and which is bent out of the plane of said link and into the plane of lever 53 so as to be engaged by said lever when the parts approach a straight line position. 5 This finger is disposed to one side of the center line of link 54 and engages lever 53 on the side thereof so that when so engaged the three pivots 63, 56 and 51 are out of alignment sufficiently to cause the swinging of the parts as the sash is 10 raised and lowered. The disposition of this finger with respect to the lever 53 is shown in Figs. 2 and 4 for the two extreme positions of the upper sash.

In the opening of the storm sash the upper sash is lowered and the two arms 33 and 34 swing 15 jointly from the position shown in Fig. 4 to another position similar to that illustrated in Fig. 3 in which the two arms are still in substantial alignment. Before the storm sash can be opened it is necessary to arrest the movement of the arm 20 34 so as to cause the swinging of the sash instead of the further movement of the arm. This is accomplished by means of a stop 67 which is formed on the arm 34 and which is adapted to engage the base 41 of the bracket 40. When the 25 lever 53 is swung, arm 34 is moved toward the sash until said stop engages the bracket 40. Further movement of the lever 53 causes the storm sash 16 to be swung outwardly upon the storm sash hangers 23 and 24. Soon after the storm 30 sash leaves the rabbett 25 the arm 34 starts swinging away from said sash until the arms 33 and 34 are in the positions shown in Fig. 2 in which the storm sash is fully open.

My invention is highly advantageous in that 35 an extremely effective and simple device is provided by means of which the storm sash may be easily opened and held in any adjusted position. The device is simple in construction and positive in operation. Where a balanced sash is employed the storm sash is automatically held in any adjusted position without the use of friction joints. The opening and closing of the storm sash is automatically accomplished by lowering 40 and raising the inner sash thereby greatly simplifying the operation.

Changes in the specific form of my invention, as herein disclosed may be made within the scope of what is claimed without departing from the spirit of my invention.

Having described my invention, what I claim 50 as new and desire to protect by Letters Patent is:

I claim:

1. A sash fastener comprising a pair of jointed arms for attachment to the sash and frame of a window, a lever connected to one of said arms for swinging the same and a link connected to said lever for operating said lever.

2. In combination with a window having a 60 frame, a sash movable relative thereto and a second sash movable relative to said frame, a pair of jointed arms, one pivoted to said first named sash and the other pivoted to said frame, a lever for swinging one of said arms and a link connected to said lever and to said second named sash and movable with said second named sash to swing said arms and move said first named sash.

3. In combination with a window having a 70 frame a sash movable relative thereto and a second sash movable relative to said frame, a pair of jointed arms, one pivoted to said first named sash and the other pivoted to said frame, a lever attached to one of said arms and a link connected to said lever and to said second named sash and

movable with said second named sash to swing said arms and move said first named sash.

4. In combination with a window having a frame a sash movable relative thereto and a second sash movable relative to said frame, a pair of jointed arms, one pivoted to said first named sash and the other pivoted to said frame, a lever immovably attached to the arm pivoted to said frame, a link connected to said lever and to said second named sash, and movable with said second named sash to swing said arms and move said first named sash. 10

5. In combination with a window having a frame, a sash movable relative thereto, and a second sash movable relative to said frame, operating means connected to said first named sash and to said frame for moving said first named sash, said operating means including a lever, and a link connected to said second named sash and to said lever operable on movement of said second named sash to move said lever and first named sash. 15

6. In combination with a window having a frame, a sash pivoted thereto, an arm pivoted to said swinging sash, a second arm pivoted to said frame and to said first named arm, said arms being adapted to jack knife, to bring the pivots thereof in proximate positions when the swinging sash is closed, means for swinging the second named arm to open the sash and means 25 operating during the opening of the sash to restrain movement of said first named arm toward the sash. 30

7. In combination with a fixed member and a movable member, an arm pivoted to said movable member, a second arm pivoted to said fixed member and to said first named arm, said arms being adapted to move in a manner to reduce the angle between the lines passing through the pivots thereof as the movable member moves toward the fixed member and means operating between said movable member and said first named arm to restrain movement of said first named arm toward said movable member during the movement of said movable member away 40 from said fixed member. 45

8. In combination with a window having a frame, a sash pivoted thereto, an arm pivoted to said swinging sash, a second arm pivoted to said frame and to said first named arm, said arms being adapted to jack knife, to bring the pivots thereof in proximate positions when the swinging sash is closed, means for swinging the second named arm to open the sash and a stop operating between said first named arm and sash during the opening of the sash to restrain movement of said first named arm toward the sash. 50

9. In combination with a double hung window comprising a frame, upper and lower sash slideable along said frame and having meeting rails and a storm sash movable relative to said frame, operating means connected to said storm sash for moving said storm sash and a member pivotally connected to the meeting rail of said upper sash at the under side thereof for operating said 60 upper sash when the lower sash is moved downwardly. 65

10. In combination with a window having a frame, a swinging sash and a sliding sash, an arm pivoted to said swinging sash, a second arm pivoted to said frame and to said swinging sash, the pivots of said arms to said sash and frame 70

substantially coinciding when said sash is closed, said arms occupying a substantially horizontal position when the sash is opened and a member operated by said sliding sash for swinging said second named arm, said member during a portion of the movement of said sliding sash toward closing position operating to move said arms into a substantially vertical position to close the swinging sash, and during the final movement of said sliding sash into its closing position operating to move said arms jointly into a substantially horizontal overlying position to lock the swinging sash closed.

11. In combination with a window having a frame, a sash movable relative thereto and a second sash movable relative to said frame, a pair of jointed arms, one pivoted to said first named sash and the other pivoted to said frame, and means fixed relative to the arm pivoted to the frame and connected to the second named sash for swinging said arms to move said first named sash upon movement of said second named sash.

12. In combination with a window having a frame, a sash movable relative thereto and a second sash movable relative to said frame, a pair of jointed arms, one pivoted to said first named sash and the other pivoted to said frame, and a lever fixed relative to the arm pivoted to the frame and connected to said second named sash for swinging said arms to move said first named sash upon movement of said second named sash.

13. A sash fastener comprising a pair of jointed arms for attachment to the sash and frame of a window, a lever fast to one of said arms and angularly disposed with respect thereto for swinging the same and means for operating said lever.

14. In combination with a window having a frame, a sash movable relative thereto and a second sash movable relative to said frame, a pair of jointed arms, one pivoted to said first named sash and the other pivoted to said frame, and a lever fast to one of said arms and angularly disposed relative thereto, and means for connecting said lever to the other sash.

15. In combination with a window having a frame, a sash pivoted thereto and another sash movable relative to said frame, a pair of jointed arms, a pivot for pivoting one of said arms to said swinging sash, a pivot for pivoting the other of said arms to the frame, said pivots being substantially the same distance from the axis of said pivoted sash and being adapted to overlie one another when the sash is closed, and means operated by the other sash for swinging said arms jointly after their pivots have been brought into register to lock the swinging sash from movement.

16. In combination with a window having a frame, a sash pivoted thereto, a second sash movable relative to said frame, an arm pivoted to said pivoted sash, means on said arm for engagement with a part movable with said sash to restrain movement of said arm relative to said pivoted sash, and means connected to said frame and second named sash for operating said arm and moving the means thereon into engagement with the part movable with the pivoted sash to initiate movement of said swinging sash.

17. In combination with a window having a frame, a sash pivoted thereto, a second sash movable relative to said frame, a mounting secured to said pivoted sash, an arm pivoted to said mounting, means on said arm for engage-

ment with said mounting to restrain movement of said arm relative to said swinging sash, and means connected to said frame and second named sash for operating said arm and moving the means thereon into engagement with said mounting to initiate movement of said swinging sash.

18. A sash operator for use with a window having a frame and two sash movable relative thereto, said operator comprising a member movably carried by said frame, an arm connected to one of said sash and a link connected to the other of said sash, said link and arm being both separately connected to said member, one thereof being adapted upon movement of the other to operate the sash to which it is connected.

19. A sash operator for use with a window having a frame and two sash movable relative thereto, said operator comprising a member pivotally mounted on the frame, an arm connected to one of said sash, a link connected to the other sash, said arm and link being separately pivoted to said pivoted member, one thereof being adapted upon movement of the other to operate the sash to which it is connected.

20. A sash operator for use with a window having a frame, a swinging sash and a sliding sash, said operator comprising a pivoted arm adapted to extend transversely of the frame when the sash are in closing position, means connected to the free end of said arm and to the sliding sash for swinging said arm, said means traveling in a direction substantially at right angles to the direction of extent of said arm when in closing position, and means operated by said arm for swinging the swinging sash.

21. A sash operator for use with a window having a frame, a swinging sash and a sliding sash, said operator comprising an arm, means carried by said frame for pivoting said arm for swinging movement, said arm being adapted to extend transversely of the frame when the sash are in closing position, means connected to the free end of said arm and to the sliding sash for swinging said arm, said means traveling in a direction substantially at right angles to the direction of extent of said arm when in closing position and means operated by said arm for swinging the swinging sash.

22. A sash operator for use with a window having a frame, a swinging sash and a sliding sash, said operator comprising a pivoted arm of a length less than the distance between the sash, said arm extending transversely of the frame when the sash are in closing position, means connected to the free end of the arm and to the sliding sash for swinging said arm, said means traveling in a direction substantially at right angles to the direction of extent of said arm when in closing position and means operated by said arm for swinging the swinging sash.

23. A sash operator for use with a window having a frame, a swinging sash and a sliding sash, said operator comprising a pivoted arm adapted to extend transversely of the frame when the sash are in closing position, connecting means connected to the free end of said arm and to one of said sash and traveling in a direction substantially at right angles to the direction of extent of said arm when in closing position, other connecting means movable with the arm and connected to the other sash, the connecting means connected to the sliding sash operating to swing said arm, and the connecting means connected to the other sash serving to swing said sash.

CHESTER O. GOSERUD. 75
